FRITZ KESSELRING, OF FURTH, GERMANY.

CONTINUOUS-CURRENT VARIABLE-SPEED MACHINE.

Application filed April 6, 1927, Serial No. 181,562, and in Germany April 15, 1926.

For certain purposes, especially for power vehicles, electric current generating plants are required, the dynamo engines of which deliver, in spite of great variations in the number of revolutions, a nearly invariable voltage or output, at any rate a voltage or output that is by far less variable than the number of revolutions.

Several proposals have already been made to solve the problem and there has been designed, in fact, a machine that has been widely used and which comprises the exciting windings which are connected up to a main brush and to an auxiliary brush arranged between the main brushes.

This dynamo machine that has become known under the name "three-brush machine" is distinguished by its great simplicity and reliability of service, but, on the other hand, it suffers from certain drawbacks enumerated hereinafter:

(1) The uniformity of the output or of the current produced leaves much to be desired, in that at average speed the average output is greatly surpassed, whereas with high numbers of revolution the current curve sinks nearly to 0.

(2) The output at a lowest number of revolutions is comparatively small so that a correspondingly heavy machine is necessary in order to obtain a certain definite amount of current at a certain small number of revolutions.

(3) Adjusting the machine to a certain definite output is difficult since slight shifting of the auxiliary brush causes a large variation of the output.

(4) The commutation conditions are very unfavorable with high numbers of revolution because then the commutating field is nearly zero or even negative.

It has been endeavored to improve the three-brush engine by making use, in addition to the exciting coils connected up to the auxiliary brush, of another set of coils of by far thinner wire connected up to the two main brushes; but however this contrivance has not been able to render the machine perfect.

The object of the present invention is to improve the three-brush machine in such a degree that actually all drawbacks inherent in the original construction are obviated, and the invention aims further at attaining this result without any increase of the cost-⁵⁵ price of the machine. The invention is based on the discovery that if a certain suitable proportion between the main poles and the auxiliary poles is chosen the decrease of the resulting flux is, owing to the saturation and the stray, by far smaller than the increase of the number of revolutions so that the resulting flux characteristic resembles approximately an equilateral hyperbola. Practically, the invention consists in designing most of the poles existing in the machine as main poles, the exciting coils of which are connected up to the main brushes, whereas the remaining poles are designed as auxiliary poles, the exciting coils of which are connected up to the auxiliary brush and to one of the main brushes; besides, the armature has series-winding and all exciting coils consist of wire of normal section.

The invention is illustrated diagrammatically and by way of example on the accompanying drawings, on which Figure 1 is a diagrammatic view of a four-pole continuous current machine designed according to this invention; Figure 2 is a similar representation showing a six-pole machine; Figure 3 is a representation of the ampere-windings and the magnetic fluxes existing and acting at various numbers of revolutions; and Figure 4 is a representation of the current curve of an existing and running machine designed strictly according to the present invention.

1, 2 and 3 (Fig. 1) are the main poles, 4 is the auxiliary pole, 5 and 6 are the main brushes, and 7 is the auxiliary brush. The exciting coils of the main poles and of the auxiliary poles are connected with the brushes in such a manner that if the armature 8 with the commutator 9 rotates in the direction indicated by the arrow the magnetic fluxes N_1 and N_3 are directed radially inwards and the magnetic fluxes N_2 and N_4 of the main pole 2 and of the auxiliary pole 4 are directed radially outwards, the main brush 5 constituting the positive pole of the machine and the auxiliary brush constituting the negative pole thereof. The auxiliary brush 7 has positive polarity with respect to the main brush 6 as long as the number of revolutions of the armature is small, but when the number of revolutions increases more and more, the polarity of the

brush 7 becomes negative and with this reversal also the direction of the magnetic flux N_4 is reversed.

The series winding of the armature is indicated by that winding element which is located between the commutator lamellæ 10 and 11 that are just being short-circuited by the auxiliary brush 7. 12, 13, 14, 15 and 16 are armature conductors. These conductors are connected with each other in series on the rear side of the armature by the wires 17 and 18, and on the front side of the same by the wires 19 and 20. The front ends of the armature conductors 12 and 16 are connected up to the commutator lamellæ 10 and 11 by the wires 21 and 22.

With the six-pole machine shown in Fig. 2 the numerals 23, 24, 25 and 26 denote the main poles, 27 and 28 the auxiliary poles, and 5 and 6 the main brushes, 7 denotes the auxiliary brush, 8 the armature, and 9 the commutator. The exciting coils of the poles are connected up to the brushes in such a manner that when the armature rotates in the direction indicated by the arrow in the centre, the magnetic fluxes in the main poles 23 and 26 and in the auxiliary pole 27 are directed radially inwards, and in the main poles 24 and 25 and in the auxiliary pole 28 radially outwards, thus forming the main brush 5 the positive pole and the main brush 6 the negative pole of the machine, and the auxiliary brush 7 has positive polarity with respect to the main brush 6 as long as the number of revolutions of the armature is small. With a high number of revolutions the polarity of the auxiliary brush is reversed, as is also the direction of the magnetic flux in the auxiliary poles 27 and 28. The exciting coils of the two auxiliary poles are connected in series by the wires 29 and 30.

Also in Fig. 2 the series winding of the armature is indicated by the winding element located between the commutator lamellæ 10 and 11 which are just being short-circuited by the auxiliary brush 7.

As the armatures have series windings, the main brushes in Fig. 1 can be shifted on the circumference of the commutator by 180° . The auxiliary brush 7 can assume, besides the position shown in the drawing, three other positions by being shifted by 90° and by 180° to the right and to the left relatively to the position shown in the drawing.

With the six-pole machine shown in Fig. 2 the main brushes 5 and 6 can be shifted for 120° and 240° without a change of their polarity. The auxiliary brush 7 can assume 5 other positions besides that shown in the drawing, the several positions being separated from one another by 60° .

Also the six-pole machine might be designed with only one auxiliary pole. If two auxiliary poles are employed, they need not lie accurately opposite each other, as in Fig.

2 his arrangement is advantageous because the magnetic attractions exerted upon the armature by all poles balance each other in pairs.

Fig. 3 shows the magneto-motive and the magnetic forces active in a machine designed according to in Fig. 1. The numerals 1, 2 and 3 indicate the main poles and 4 indicates the auxiliary pole. N_3 and N_4 , as well as N_1 and N_2 , are the magnetic fluxes of these poles, the direction of which is indicated by arrows. A_{t3} and A_{t4} , as well as A_{t1} and A_{t2} , are the magneto-motive forces by which the fluxes mentioned are produced. The fluxes N_3 and N_1 enter into the armature where then a division takes place, in that a part turns to one of the adjacent poles and the other part turns to the other of these poles. Thus, the flux N_1 is divided into the parts $N_{4/1}$ and $N_{1/2}$. The fluxes $N_{2/3}$, $N_{3/4}$, $N_{4/1}$ and $N_{1/2}$ form the magnetic circle proper and are produced by the total of the ampere-windings which encompass them. It may be supposed in what follows that the ampere-windings and the fluxes are positive when they have the direction indicated by the arrows in Figs. 1 and 3, whereas they are negative in the opposite direction. $N_{3/4}$ is produced by A_{t3} and A_{t4} , $N_{4/1}$ by A_{t4} and A_{t1} , and so on. For the sake of simplicity it is assumed in this example that with a minimum number of revolutions $n=n_0$ all magneto-motive forces and all fluxes are equally strong and positive, that is to say: $A_{t3}=A_{t4}=A_{t1}=A_{t2}$ and

$N_{2/3}=N_{3/4}=N_{4/1}=N_{1/2}$. And there may be assumed furthermore, that the saturation, as well as the stray, exert no influence. Below the poles the values are stated in the form of rectangles which, being positive, lie all above the abscissa axis O—O. As has already been said in one of the preceding paragraphs, the polarity of the auxiliary brush decreases, with respect to the main brush 6, with the increase of the number of revolutions, becomes finally zero, and changes thereafter its direction if the number of revolutions increases still more. Owing thereto, with a number of revolutions $n=n_1$, A_{t4} will be 0; with a higher number of revolutions $n=n_2$, the ampere-windings of the auxiliary pole will be $-A_{t4}$. In the case of $n=n_3$, they will become $-2A_{t4}$; in the case of $n=n_4$, they will become $-3A_{t4}$, and so on. These 4 cases are also graphically represented in Fig. 3. The fluxes $N_{2/3}$ and $N_{1/2}$ are the same for all numbers of revolution; the fluxes $N_{3/4}$ and $N_{4/1}$ become smaller and smaller with the increase of the numbers of revolution, become then zero, and with still higher numbers of revolutions, finally negative. As with $n=n_1$ and $A_{t4}=0$, A_{t1} and A_{t3} remain, however, unchanged, $N_{3/4}$ and $N_{4/1}$ become only one half of what they

would be as with $n=n0$, and as with $n=n2$, At4 is as great, but reversely directed than with $n0$, $N3/4$ and $N4/1$ become zero. Furthermore, as with $n=n3$, At4 is twice as great and inversely directed than with $n0$, $N3/4$ and $N4/1$ will become only half so great and be directed inversely as with $n0$. And as, finally, with $n=n4$, At4 is three times as great as with $n0$, and inversely directed, $N3/4$ and $N4/1$ will be equally great, but inversely directed than with $n0$. If the resulting flux at $n=n0$ amounts, for instance, to 400,000 lines of force, it is diminished at $n1$ to 300,000, at $n2$ to 200,000, at $n3$ to 100,000, and at $n4$ to 0. As in reality, with suitable dimensions, neither the stray, nor the saturation must be neglected, the picture changes in reality about as indicated in dotted lines for $n=n3$ and $n=n4$, that is to say, the negative fluxes are smaller than those that have been theoretically ascertained. The resulting fluxes decrease in reality nearly like an equilateral hyperbola so that, in fact, the output of the machine remains constant even at very large variations of the number of revolutions.

The output at a minimum number of revolutions is, with the present improved machine, greater than with a three-brush machine, from the reason, as with the improved machine the excitation need not, as with said other machines, be weak in comparison to the armature ampere-windings. The output of the machine depends, therefore, solely upon the admissible heating.

When a machine of the improved construction has been adjusted for a certain definite output the adjustment is by far less liable to an alteration than is the case with the three-brush machine, because the auxiliary brush can be located in more nearly the middle than with other machines.

The commutation conditions are, with higher numbers of revolution more favorable from the reason, that with the highest number thereof most poles are excited constantly so that it is easily possible to obtain a favorable commutation field by a suitable shape of the pole shoes.

Fig. 4 shows a current-curve of an existing machine designed and used for motor-car lighting. This machine has been connected

up in parallel with a 12-volt battery. The numbers of revolution have been inscribed on the abscissa, and the current strengths on the ordinate. J denotes the current generated by the machine; it is apparent that it remains nearly constant from 1400 up to 4000 revolutions per minute. $i1=i2=i3$ is the constant exciting current of the main poles 1, 2 and 3. $i4$ denotes the exciting current of the auxiliary pole 4.

This pole is positive at 650 revolutions, becomes smaller when the number of revolutions increases, becomes zero at $n=1400$, reverses its direction and increases when the number of revolutions increases, as already described. The theoretical representation in Fig. 3 has been confirmed fully by the built machine that has been tested in every respect.

I claim:

1. A continuous current machine adapted to run with variable numbers of revolutions and with approximately invariable voltage and comprising a field magnet system composed of main poles and of auxiliary poles, main brushes and a third brush, the exciting coils of said main poles being branched from said main brushes, and the exciting coils of said auxiliary poles being branched from one of the main brushes and said third brush, the armature having a series winding, and the number of the said auxiliary poles being smaller than that of the said main poles, substantially as described.

2. A continuous current machine adapted to run with variable numbers of revolutions and with approximately invariable voltage and comprising a field magnet system composed of main poles and of auxiliary poles, all poles together amounting to six; main brushes and a third brush, the exciting coils of said main poles being branched from said main brushes, and the exciting coils of said auxiliary poles being branched from one of the main brushes and said third brush, the armature having a series winding, the number of the said auxiliary poles being smaller than that of the said main poles and two of the auxiliary poles being arranged diametrically opposite to one another, substantially as described.

FRITZ KESSELRING.
